Primary Examiner—Raphael Barkai
Attorney, Agent, or Firm—Warner Norcross & Judd LPP[57] CLAIM

The ornamental design for matte lipstick case, as shown and described.

DESCRIPTION

FIG. 1 is a perspective view of the matte lipstick case embodying the new design;

FIG. 2 is a front elevational view thereof, the rear elevational view being the mirror image thereof;

FIG. 3 is a left side elevational view thereof, the right side elevational view being the mirror image thereof;

FIG. 4 is the top plan view thereof; and,

FIG. 5 is a bottom plan view thereof.
